(57) **CLAIM**

The ornamental design for a carpometacarpal thumb brace, as shown and described.

DESCRIPTION

FIG. 1 is a bottom perspective view of a carpometacarpal thumb brace, showing my new design in a strapped configuration;

FIG. 2 is a bottom plan view of FIG. 1;

FIG. 3 is a top plan view of FIG. 1;

FIG. 4 is a left-side elevational view of FIG. 1;

FIG. 5 is a right-side elevational view of FIG. 1;

FIG. 6 is a front elevational view of FIG. 1;

FIG. 7 is a rear elevational view of FIG. 1;

FIG. 8 is a bottom perspective view thereof, illustrated in an unstrapped configuration;

FIG. 9 is a bottom plan view of FIG. 8;

FIG. 10 is a top plan view of FIG. 8;

FIG. 11 is a left-side elevational view of FIG. 8;

FIG. 12 is a right-side elevational view of FIG. 8;

FIG. 13 is a front elevational view of FIG. 8; and,

FIG. 14 is a rear elevational view of FIG. 8.

The broken lines showing a person's hand in the figures depict environmental matter and form no part of the claimed design. The remaining broken lines represent stitching, and are part of the claimed design.

1 Claim, 12 Drawing Sheets
